UNITED STATES PATENT OFFICE.

RUFUS J. COLE, OF PASADENA, CALIFORNIA.

PROTECTIVE SHIELD FOR SHOE-LACE HOOKS.

1,185,483.

Specification of Letters Patent. Patented May 30, 1916.

Application filed February 8, 1915. Serial No. 6,738.

To all whom it may concern:

Be it known that I, RUFUS J. COLE, a citizen of the United States, residing at Pasadena, in the county of Los Angeles and 5 State of California, have invented new and useful Improvements in Protective Shields for Shoe-Lace Hooks, of which the following is a specification.

My invention relates more specifically to 10 a hook end guard for shoe lace hooks, and an important object is to provide a guard preferably formed of a single piece of material that may be mounted on a shoe, whereby the free end of the hook will be prevented from becoming entangled in strings, 15 cords, rope, brush or like foreign material.

A further object of my invention is to provide a guard which may be readily applied to a shoe or boot, and which will not 20 prevent easy and ready engagement of the boot laces to the hooks.

Heretofore shoes, and particularly hunting boots have been provided with lacing hooks in order to expedite the lacing operation of the boot by the wearer, but the advantage of easy and ready lacing has been nullified by the disadvantages accruing to the wearer when passing through forests and 25 rough country, as the free ends of the hooks become entangled with twigs, brush, cords and other material, making walking difficult, breaking and bending the hooks, and sometimes tripping the wearer.

By means of my improved guards the 30 above recited disadvantages are obviated, as the guards prevent engagement with obstructions, and at the same time permit the ready engagement and disengagement of the laces to and from the hooks.

40 The accompanying drawing illustrates embodiments of my invention in which:

Figure 1 is a perspective view of the hook. Fig. 2 is a vertical cross section of the hook shown in Fig. 1. Fig. 3 is a plan view of 45 a hook showing a modified fastening means. Fig. 4 shows my improved hook applied to a boot.

Referring to the drawings and more particularly to Figs. 1 and 2 which illustrate a 50 combined hook guard construction, 1 designates a guard member, 2 a hook formed integral therewith, the base being provided with securing means 3 and 9 for ready at-

tachment to the material forming the boot or shoe. As clearly shown in Fig. 2, the 55 guard 1 comprises a flat base portion 6, an up-bent portion 5, and a returned bent portion 4. The guard is shown as a crescent shaped member which has its lower side in one plane and its upper side partly in another plane which is substantially parallel to the lower plane. The ends of the crescent shaped member taper toward the bottom of the standard 7, thus forming with the hook 2 a channel to receive the lace. The guard 60 which forms a shield for the hook which effectually turns aside any foreign material such as fibers, twigs, strings or cord which would enter a hook not provided with my improved guard, and yet permits ready 65 engagement of the lace. The hook 2 consists of a standard 7 and an inbent hook end 8 which is here shown as a concaved disk. My guard may be attached to the material by any well known means, a convenient one 70 being an eye 3 which is concentric with the disk 8, or if desired, the fastening means may consist of prongs 10, as shown in Fig. 3. Prongs are forced through the fabric and bent backward. As additional means an eye 75 9 may be added if desired.

The structure shown is preferably made of stamped metal, such construction being light and economical to manufacture, but various other well known means of forming 80 my novel guard and hook may be used.

What I claim is:—

1. The combination of a vertically disposed standard, the end being turned substantially at right angles to said standard 90 to form a hook, a hook guard member of crescent form so disposed that the hook lies partially within the concavity of said guard with the upper edge lying in substantially the same plane as the hook, there being a 95 channel formed between the hook and guard to permit the insertion therein of a shoe lace.

2. A combination shoe lace hook and guard therefor, comprising an integral member formed of sheet metal having a base with 100 attaching means, said base formed with a vertically disposed standard extending upwardly therefrom, the end being turned substantially at right angles to the standard to form a hook, a hook guard formed on said 105 base by an indentation therein providing a

2
crescent guard so disposed that the hook lies within the concave portion of said guard with the upper edge of said guard lying in substantially the same plane as the hook member, there being a channel formed between the hook and guard to permit the insertion therein of a shoe lace.

In witness that I claim the foregoing I have hereunto subscribed my name this 28th day of January, 1915.

RUFUS J. COLE.
